CLAIM

The ornamental design for a swimming pool valve, as shown and described.

DESCRIPTION

FIG. 1 is a front and top perspective view of a swimming pool valve, showing my new design;
 FIG. 2 is a rear and bottom perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof; and,
 FIG. 8 is a bottom plan view thereof.

The broken lines in the figures illustrate portions of the swimming pool valve that form no part of the claimed design.

1 Claim, 8 Drawing Sheets
